CHIMNEY BLOCK

Lloyd V. Parsons, Seattle, Wash.

Application April 2, 1951, Serial No. 218,876

2 Claims. (Cl. 98—78)

1

This invention relates to improvements in chimneys of those general forms of construction used in residences for the conduction of smoke and gases from furnaces, stoves, fireplaces and the like and also applicable to factory stacks and chimneys; the invention having reference more particularly to a chimney top or topping block.

It is the principal object of the invention to provide a chimney top or block designed for application to the top end of a chimney as a means of overcoming that down draft and downward acting air pressure in the chimney that is usually created by wind or air currents and which is detrimental to proper and efficient operation of the stove, fireplace or furnace that is accommodated by the chimney.

It is a further object of the present invention to provide a chimney topping block that will, in the event of a wind blowing past or across the chimney top, induce an updraft in the chimney flue instead of causing a downdraft or retarding pressure therein.

More specifically stated, the present invention resides in the provision of a chimney topping block with a passage leading upwardly therethrough and which block has its side walls formed with openings leading inwardly and upwardly into the block passage, and there being a baffle suspended in the block passage in a manner and at such a location that wind or cross currents or air will be checked or deflected through the block in a manner that will induce an upward draft in the chimney flue.

Further, it is an object to so construct baffles and to so dispose them in the block flue that any downdraft entering the top of the chimney will be deflected outwardly through the wall passages.

Still further objects of the invention reside in the details of construction and combination of parts employed in the construction of the present block, both in its preferred form and in alternative forms of constructions.

In accomplishing these and other objects of the invention, I have provided the improved details of construction, the preferred forms of which are illustrated in the accompanying drawings, wherein—

Fig. 1 is a perspective view showing a chimney top or topping block embodying the features of the present invention therein, as applied to a chimney.

Fig. 2 is a vertical, cross-section of the same.

Fig. 3 is a perspective view of a baffle designed for use in the present chimney block, and like that used in the block shown in Figs. 1 and 2.

2

Fig. 4 is a vertical cross-section of the chimney block of the present invention, equipped with a baffle of an alternative form of construction.

Fig. 5 is a perspective view of the baffle which is shown in the chimney block of Fig. 4.

Fig. 6 is a plan, or top view of the present chimney block as equipped with a baffle of still another form of construction.

Fig. 7 is a perspective view of the baffle used in the block shown in Fig. 6.

Fig. 8 is a perspective view of a closure baffle or plate for the top end of the chimney block.

Referring more in detail to the drawings—

Chimney topping blocks of the present kind may be made in various sizes, determined by the dimensions of the chimneys to which they are to be applied. In the present illustrations, and more particularly as understood by reference to Fig. 6, the topping block is made for application to a chimney that, in plan, is rectangular but not square. However, whether square or rectangular in the proportionate dimensions shown, or other proportionate dimensions, the construction of the block and its mode of use would be substantially the same as that shown.

It is also to be explained that while the present chimney topping block can be made as a single piece, it is preferred that it be cast of cement in two or more sections to facilitate the molding operation and withdrawal of parts from the molds.

In its present preferred form of construction, the topping block, which is designated in its entirety by reference numeral 10 comprises a base section 10a and a top section 10b. The base section is of rectangular form in plan or in its horizontal dimensions and these correspond to the outside dimensions of the chimney on which it is to be disposed. In Figs. 1 and 2 the upper end portion of a chimney is designated at 11 and the flue or passage therein is designated at 12. The topping block 10 is mounted in the usual mortar joint 13 on the top end of the chimney as seen in Fig. 2.

The base section 10a of the block is formed with a passage 15 vertically therethrough to provide an upward continuation of the chimney flue passage; this passage 15 being somewhat tapered in an upward direction and it is to be observed by reference to Fig. 2 that the chimney flue passage is of lesser width than the lower end of the passage 15, thereby providing an enlarged chamber in the block as a gas collecting space.

The upper section 10b of the block has a central passage 16 leading upwardly therethrough

as a continuation of the passage 15. Passage 16 has vertical side walls from its lower end to above the center of the section and there the passage is outwardly flared as at 16', to its upper end. The outer surface as at 17 and 18 is beveled or curved for a specific purpose which will hereinafter be pointed out.

In the showing in Fig. 2, the side surfaces of the passage 15' are curved. In the showing in Fig. 4, they are flat surface. The formation of these surfaces is more or less a matter of choice. However, it is quite desirable that the upper end of passage 16 be flared as is herein shown in Figs. 2 and 4.

The block section 10b is mounted upon section 10a in a mortar joint, as at 20. When the block sections are thus assembled on the chimney, the block provides, in effect, an upward continuation of the chimney and its flue or passage.

Formed in the opposite side walls of the block as well shown in Fig. 2, are inwardly and upwardly directed air passages 25. These are of substantial size and of rectangular form as understood by their outer end showing in Fig. 1. Also, each passage has its top surface upwardly inclined at a steeper angle than the lower surface so that the passages are inwardly and upwardly flared. These passages preferably are formed in all four walls of the block and are directly oppositely disposed in its opposite walls.

Suspended in the passage 16 of the upper section of the block, is a baffle 28. As seen in Fig. 3, the baffle comprises a cast piece of cement, of pyramid form. Its base dimensions are just slightly less than the corresponding dimensions of the passage in which it is suspended. The block is suspended by means of hanger rods 30 embedded therein at its four corners. The upper end portions of the rods are outwardly bent, as at 30x to holdingly engage the outwardly sloping surfaces of the block passage 16' as seen in Fig. 2. The position of suspension of the baffle 28 is about midway of the inner ends of the passage 25. Thus air currents directed down the passage 16, as indicated by the direction arrows 31 in Fig. 2, will be diverted by the inclined top surfaces of the block, out through passage or passages opposite those at the side from which the wind is blowing. This deflection of air creates a suction, or updraft through the chimney instead of forcing air downwardly therein.

Baffles used in the block passage can be made in various forms such, for example, as those shown in Figs. 5 and 7. The device of Fig. 5 is of metal and comprises opposite end plates 34-34, in parallel, vertical relationship and held rigidly in spaced relationship by a plurality of cross-louvers 35 arranged as best shown in Fig. 4. The opposite end plates are formed with outwardly directed flanges 36 across their upper edges adapted to engage against the outwardly sloping walls of the upwardly diverging portion of the block passage 16 for functional support of the baffle. A ridge shaped baffle 38 joins the end plates across their lower edges to divert down flowing air currents laterally, to the side passages, and prevent downflow in the chimney. The louvers 35 are arranged in spaced relationship above and at opposite sides of the baffle 38 and are downwardly and outwardly inclined, thus to divert down flowing air in a lateral direction as has been indicated by the direction arrows in Fig. 4.

The baffle plate 40 shown in Figs. 6 and 7 is designed for support horizontally in the upper end

of passage 16 to stop any down flow of air currents directed into the upper end of this passage. The baffle comprises a flat plate with semi-circular recesses 41 along its edges permitting relief of pressure of gases rising through the block, yet without permitting down pressing air currents to enter to any detrimental extent.

The baffle plate 45 of Fig. 8 is used like that in Fig. 6 but is designed to fully close the upper end of the passage 16. All baffles shown are easily and readily removable from the block by lifting them upwardly therefrom.

By reference to Figs. 1 and 2 it will be noted that the exterior of the upper end of section 10b is formed with the outwardly projecting concave surfaces 17 and 18 which extend completely about the block. In Fig. 4 I have illustrated a modified form which is found to be equally satisfactory. In this form the surface 17a and 18a extend angularly from the main portion of the block. The purpose of the outwardly extending rim is to provide a deflecting means for breaking up the air which strikes against the side of the block. Instead of causing a downward pressure in the chimney the diverted air currents induce an upward flow of air from the heating unit thereby removing pressures that may exist.

Assuming the chimney block to be so constructed and applied to the chimney it will be understood to afford the following advantages:

All down draft caused by wind blowing into the upper end of the chimney will be eliminated, and by reason of the use of the present baffle block in the relationship to the block passages as shown, will induce an updraft in the flue. This results in better burning in the stove, furnace or fireplace which is served by the chimney. Also, it removes the possibility of explosions from the ignition gases which often collect in a chimney.

A further advantage of employing a chimney block on the top of the chimney is that it permits the height of the chimney to be reduced. To eliminate down drafts and pressures in a chimney, it is common practice to extend the height of the chimney above the roof or other objects which obstruct the free flow of air. This raises the chimney opening above the turbulent air conditions that may be created by such obstruction. However, with my chimney block, such additional cost and construction is not required because of the means which it provides for overcoming the down drafts or pressures within the chimney. Further the reduced height of the chimney enhances the appearance of the building.

Having thus described my invention, what I claim as new therein and desire to secure by Letters Patent is:

1. A cast concrete chimney block of the character described adapted to be mounted on the top of a chimney and comprising a base section and a top section disposed on the base section; the base section being formed with an upwardly tapered flue passage adapted to register with the chimney flue, and being substantially larger at its lower end than the chimney flue, and substantially of the same size at its upper end, said top section being formed with a flue passage which is a continuation of the base section flue passage and which has the upper end portion thereof outwardly flared; opposite side walls of the chimney block having passages opening upwardly therethrough into the flue passage of the block at a common level, and a baffle of pyramid form removably suspended in the flue passage of the top section within the top and lower edge

limits of the open inner ends of the side wall passages to stop direct downward flow of air currents into the chimney flue.

2. A chimney block as in claim 1 wherein the top section is formed externally with an outwardly projecting rim to deflect air currents which strike the side walls of the block.
